JOHN C. CLARKE, OF JERSEY CITY, NEW JERSEY.

Letters Patent No. 71,708, dated December 3, 1867.

IMPROVEMENT IN TEMPORARY BINDERS FOR MUSIC, &c.

The Schedule referred to in these Letters Patent and making part of the same.

TO ALL WHOM IT MAY CONCERN:

Be it known that I, JOHN C. CLARKE, of Jersey City, Hudson county, New Jersey, have invented a new and useful Improvement in Portfolio for Newspapers, Periodicals, Music, &c.; and I do hereby declare that the following is a full, clear, and exact description thereof, which will enable others skilled in the art to make and use the same, reference being had to the accompanying drawings, forming part of this specification, in which—

Figure 1 is a view of my improved portfolio open, and showing in red lines the manner in which the music, &c., is attached.

Figure 2 is a cross-section of the same, closed and filled.

Similar letters of reference indicate corresponding parts.

My invention has for its object to furnish an improved portfolio, so constructed and arranged that the periodicals, &c., may be easily attached, securely held, and readily removed, when desired; and it consists in the combination of the rigid metallic back plate, having cross-slots formed in its end, and the hinged side plates, by which it is connected with the cover with each other, and in the combination of the cord or cords for securing the contents of the portfolio in place with the slotted back plate; the whole being constructed and arranged as hereinafter more fully described.

A are the sides, and B the flexible back of the portfolio, about the construction of which there is nothing new. C is a rigid metallic back, to the side edges of which are hinged the edges of the side plates D, as shown in figs. 1 and 2. The side plates D are secured to sides A of the cover by means of rivets, or in some other convenient and substantial manner. In the ends of the back plate C are formed cross-slots e', or holes, for the passage of the cord E, by means of which the periodicals, music, or other contents of the portfolio are secured in place.

The cord E may be continuous, that is to say it may be passed through the slot at one end of the back plate C, then along the said plate, through the slot at its other end, along the other side of the plate, and so on, until enough turns have been made to hold the intended contents of the portfolio. The cord E may be elastic or inelastic, as may be preferred, and, if desired, instead of being continuous, each cord may make but a single turn. The music, periodicals, &c., are attached by passing them through a loop of the cord E, so that the said cord may rest in the central fold of the music or periodical, as shown in red in figs. 1 and 2. When thus attached, the music or papers are read in the order in which they are placed, in the same manner as the consecutive pages of a book are read.

I claim as new, and desire to secure by Letters Patent—

1. The combination of the rigid metallic back C, having cross-slots e' formed in it, and the hinged side plates D with each other, substantially as herein shown and described and for the purpose set forth.
2. The combination of the cord or cords E with the slotted back plate C, substantially as herein shown and described and for the purpose set forth.
3. The combination of the slotted back plate C and hinged side plates D with the side boards A and back B of the cover, substantially as herein shown and described and for the purpose set forth.

B of the cover, substantially as herein shown and described and for the purpose set forth.

The above specification of my invention signed by me, this 18th day of June, 1867.

JOHN C. CLARKE.
